SASH FRAMES WITH TWO OR MORE WINDOW PANES

Eric Sigfrid Persson, Malmo, Sweden

Application May 20, 1952, Serial No. 288,917

Claims priority, application Sweden June 20, 1951

4 Claims. (Cl. 20—56.5)

To a modern window belongs in most uses a screening means of some kind or other, such as a Venetian blind, jalousie or curtain. The screening means may be regarded as an integral part of the window, which may be manufactured on a factory scale with the screening means incorporated therein. In order to make the manufacture on a factory scale economical, it is necessary to achieve great simplicity in the construction, so that the manufacturing methods may become simple and rational.

The present invention involves a step in the endeavours to provide a modern window of great constructive simplicity. The invention relates to a sash frame, generally with two window panes in the same frame. The substantial distinguishing feature of the invention resides, above all, in that the frame comprises a frame member extending along one whole side and along the whole or a substantial portion of two further sides of the window while forming round corners in the transitions between said sides, in which frame member the window panes are tightly mounted at three of their edges, whereas a straight frame member extends along the fourth side of the window, said latter frame member being removably connected to the firstmentioned frame member and forming a holder for or a head of a Venetian blind or other screening means.

The invention provides a window which, disregarding the window panes, only consists of two main portions, that is to say, the bent frame member and the screening means. The straight frame member may be regarded as belonging to the screening means, inasmuch as it may form the head of the latter, that is to say, is made to carry the screening part or parts and comprises members for the pulling of the screening means across and back, as well as members for other control of the same. If the bent frame member like the straight frame member consists of a sectioned metal bar, the same section may be brought into use in both cases.

The mechanical equipment required for the manufacture of a window of this description will be very simple, particularly so as only the form of a single metal section calls for consideration. Soldered and welded joints may be avoided, inasmuch as two corners of the sash frame are produced by round-bending of a straight metal section at two points, while the two remaining corners, which are right-angled, are formed between the shanks of the bent frame members and the ends of the straight frame member, which are removably secured to said shanks. Contributive to the simplicity of the structure is also the circumstance that the straight frame member forms a bordering for the window panes, namely at an edge of the latter, while also constituting a holder or head of the Venetian blind or other screening means made use of, that is to say, answers two principal objects at the same time.

By the fact that two glass panes are mounted in the same frame, it is possible to achieve good outward sealing of the intermediate space between the panes, so that this space may remain relatively free from dust. Hereby

2

cleaning of the sides of the window panes facing said intermediate space will be unnecessary or may be brought down to a minimum. By the possibility of loosening the straight frame member the advantage is also obtained that these surfaces are also made accessible to cleaning should this prove necessary some time or other.

The screening means may be arranged as desired between the window panes or inside the inner one of the panes. If the screening means is arranged between the panes, the operation of the same will still be simple, inasmuch as the requisite operating members are provided on the straight frame member, which forms a holder for or a head of the screening means. In spite of the fact that the screening means is arranged between the window panes, it is accessible for repair and other supervision through the removable arrangement of the straight frame member.

In countries with a colder climate, it might be found necessary to prevent the passage of cold from the outside of the window to the inside thereof, as otherwise steam might condense on the inside of the sash frame to the detriment of the building. A preventive may be attained by dividing the frame into an outer part frame and an inner part frame, which are separated by an insulating packing. Such an insulation of the inside of the frame from the outside thereof need not increase the manufacturing cost to any appreciable extent, particularly if the joining of the outer part frame with the inner one is carried out by mechanical means in connection with the working procedure during which the corners of the bent frame members are being shaped.

Sealing against a surrounding frame or against the borders of the opening in the wall of the building wherein the window is inserted may be achieved in a simple manner in connection with the invention by the frame member consisting of metal sections being provided with flanges projecting outwardly from the webs of the metal sections in planes extending in parallel to the plane of the window panes. In movable windows, these flanges form abutments against a rabbet in a frame or the like and may for the attainment of the requisite sealing be provided with a packing which may be folded over the edge of the flange.

A few examples of applying the invention are illustrated by way of diagrammatic representation in the accompanying drawing. Fig. 1 shows a front view of the sash-frame in its mounted state, and Fig. 2 is a similar view with the straight frame member removed and raised. Fig. 3 shows the frame in the same manner as Fig. 1 but with the screening means in screening position. Figs. 4, 5 and 6 each show a form of embodiment of the sash-frame in cross section.

As shown in the drawing, the sash-frame consists, first, of a frame member 10 extending along a whole side, the lower side according to the drawing, and two whole further sides (the vertical sides) of the window, the transitions between said sides forming round corners 12, and, second, of a straight frame member 14 extending along the fourth side, here the upper side of the window. As shown in Fig. 2, the straight frame member 14 is removably connected to the bent frame member 10 so as to permit of being raised from the latter. Two glass panes 16, 18 are tightly mounted at three edges into the bent frame member. The straight frame member having the fourth edge of the glass panes framed into the same forms a holder for or a head of a Venetian blind or other screening means 20, which is shown in Fig. 3 in its pulled-across position. The Venetian blind may be conceived of as being arranged on the straight frame member so as to be located between the panes or inside the inner pane.

The frame members 10, 14 consist of metal sections, which are provided with channels 22, 24 having the win-

dow panes 16, 18 inserted into the same with a tight fit. The intermediate space 26 between the panes will thus be tightly closed and relatively free from dust, whereby the need for cleaning is appreciably diminished. Should cleaning be required some time or other, it can nevertheless be performed in a relatively simple manner by loosening and raising the removable straight frame member, which may be secured to the shanks of the frame member 10 by means of screws. The Venetian blind will accompany the straight frame member, and is thus also readily accessible for supervision, exchange or repair.

The frame is provided with a projecting flange forming an abutment against a frame or a wall surface about the opening having the sash-frame mounted therein. The flange may be located differently, depending on whether a movable or rigidly arranged window is in consideration, and in the first case depending on whether the window is mounted on horizontal pivot axes or is laterally suspended. The flange extends in a plane paralleling the plane of the window panes. Fig. 4 shows a flange 26' on the frame member 10 near the outside thereof. If this frame is pivotally suspended about a horizontal axis approximately at the middle of the window, the flange 26' extends upwardly along the vertical sides approximately to the pivot axis and corresponds to a similar flange or abutting edge on the frame above the pivot axis. In connection with a laterally suspended window, a flange 28 may be provided round the frame, as shown in Fig. 5.

In the embodiment shown in Fig. 6, the frame is divided into an outer part frame 10a and an inner part frame 10b, which are cold-insulated from each other by a packing 30 in a channel in the one part frame, an edge on the other part frame projecting into said channel. Here, the part frame 10b is shown with a flange 32 having a packing 34 folded over the same, said packing having for its object to afford sealing between the frame and the surrounding frame or wall surface. The connection between the part frames 10a, 10b may be obtained by the channels of corresponding metal sections being compressed against the intermediate packing, for instance by rolling along the sections for the whole length thereof or by pressing the material inwardly at certain points separated from each other. This may be effected by mechanical means, the frame members 10a, 10b then forming an integral frame of the same shape as the frame member 10 in Figs. 1 and 5. Obviously, the straight frame member forming a lintel of the frame is constructed in a corresponding manner in the form of two members 14a, 14b, which are joined with a packing 36 therebetween. This frame piece is removably secured to the frame 10a, 10b and may form a holder for or a head of a Venetian blind or other screening means, as in the preceding embodiment.

Although the invention is shown in the drawing as being applied to windows having two panes inside one another, the invention is not limited to this construction, but may also be utilized with three panes. Otherwise, the invention also is not restricted to the embodiments shown diagrammatically in the drawing; these embodiments only representing simplified examples.

What I claim is:

1. A sash-frame for windows comprising a frame member extending along a whole side of the window and two further sides thereof while forming round corners in the transitions between said sides, said frame member

further having channels for holding three edges of each of two spaced window panes; a straight frame member having corresponding channels for said panes and extending along the fourth side of the window and means to connect said straight frame member removably with the first-mentioned frame member, the straight frame member being formed as a holder for a screening means to be inserted between the window panes.

2. A sash-frame for windows comprising a sectioned metallic frame member extending along a whole side of the window and along substantially the whole length of two further opposite sides thereof while being bent to form round corners in the transitions between said sides, said frame member further being formed with channels for tightly holding three edges of each of two parallel spaced window panes, a straight sectioned metallic frame member having corresponding channels for said panes and extending along the fourth side of the window, means to removably connect said frame members at the ends thereof, said straight frame member comprising operating means mounted to permit operation of a screening member intended to be inserted into the space between the window panes.

3. A sash frame for windows comprising an outer metallic frame member extending along a whole side of the window and along two further sides thereof while forming round corners in the transitions between said sides, an inner metallic frame member extending parallel with said outer frame member, each of said frame members having a channel for three edges of a window pane, cold insulating means between said outer and inner frame members, and a further straight metallic frame member removably connected with the first-mentioned frame members and comprising an outer part and an inner part and heat insulating means between said parts, said straight metallic frame member having corresponding channels for said panes and being formed as a holder for screening means to be inserted between the window panes.

4. A sash frame for windows comprising a sectioned metallic frame member extending along a whole side of the window and two further sides thereof while forming round corners in the transitions between said sides, said frame member further being formed with a web and channelled edge portions for receiving two parallel spaced panes and a flange extending outward from the web in a plane parallel with those of said panes, a straight frame member having corresponding channels for said panes and extending along the fourth side of the window, and means to connect said straight frame member removably with the first-mentioned frame member, the straight frame member forming a holder for a screening means to be inserted between the panes.
